UNITED STATES PATENT OFFICE.

CHARLES I. OWEN, OF YONKERS, NEW YORK.

DISPLAY DEVICE.

1,385,225.

Specification of Letters Patent. Patented July 19, 1921.

Application filed December 11, 1919. Serial No. 344,051.

To all whom it may concern:

Be it known that I, CHARLES I. OWEN, a citizen of the United States, and a resident of Yonkers, in the county of Westchester 5 and State of New York, have invented a new and Improved Display Device, of which the following is a full, clear, and exact description.

The object of the invention is to provide 10 a new and improved display device more especially designed for displaying burial and similar garments, and arranged to protect the garments against dust, to permit of conveniently changing the garments on 15 the forms, and to display the garments to the fullest advantage.

In order to accomplish the desired result, use is made of a form adapted to support a 20 garment and having a flat bottom and a flat back, a base and a back plate attached to the said base, the bottom of the form being secured to the said base, the back of the form being secured to the said back plate, the latter forming a background for the dis- 25 played garment.

A practical embodiment of the invention is represented in the accompanying drawings forming a part of this specification, in which similar characters of reference indicate corresponding parts in all the views.

Figure 1 is a perspective view of the display device in open or display position;

Fig. 2 is an enlarged sectional side elevation of the same with the parts in folded 35 position and the garment removed from the form;

Fig. 3 is a sectional plan view of the same on the line 3—3 of Fig. 2;

Fig. 4 is an enlarged sectional side elevation of the hinged connections between the front and the bottom of the container and between the front and the back plate;

Fig. 5 is a perspective view of a modified form of the display device; and

Fig. 6 is an enlarged sectional side elevation of the same.

The garment 10 to be displayed is draped on a half form 11 preferably made hollow and having a flat bottom 12 and a flat back 13. The bottom 12 of the form 11 is secured 50 by eyelets or other suitable fastening means 14 to the front 15 of a box 16 having the usual bottom 17, back 18, sides 19 and a removable cover 20. The front 15 is provided 55 at the inner face adjacent the sides with cleats 21 to stiffen the front and to fit against

the inner faces of the sides 19 to hold the front 15 securely in place when in closed position, as shown in Figs. 2 and 3.

The front 15 is connected at its lower 60 edge by a hinge 25 with the front end of the bottom 17 of the box 16 to permit of swinging the front 15 downward into horizontal position to support the form 11 in upright position, as plainly indicated in Fig. 65 1 and in dotted lines in Fig. 2. It will be noticed that the front 15 now forms a base for the form 11 and the garment 10 draped on the form 11. A hinge 26 connects the lower end of the front 15 with a back plate 27 to 70 which is detachably secured the back 13 of the form 11 by the use of suitable tying strings 28 or similar tying devices. It is understood that in order to drape a garment 10 on the half form 11 the tying strings 28 75 are opened and the back-plate 27 is swung out of engagement with the flat back 13 of the half form to allow of convenient and accurate placing of the garment in position on the half form. When this has been done, 80 the backplate 27 is fastened by the tying strings 28 to the half form. It will be noticed that the back plate 27 fits into the box 16 and projects beyond the sides and top of the form 11 and the garment displayed 85 thereon so that the back plate 27 forms a background for the garment to heighten the appearance thereof. It will also be noticed that when the back 13 of the form 11 is secured to the back plate 27 and the front 15 90

is swung downward and outward then the back plate 27 swings forward and upward as it is fastened to the form 11 which in turn is fastened to the front 15. Thus by the arrangement described the form 11 and the 95 garment 10 can be readily swung into display position and when not in use the form and the garment are safely stored within the box 16 and protected from dust and other extraneous matter. It will further be noticed that when the parts are in folded position the cover 20 holds the front 15 closed, and when it is desired to display the garment the cover is first removed and then the front 15 and the back 27 are swung outward to 100 display the burial garment 10 in upright position.

In the modified form shown in Fig. 6, the form 30 has its bottom 31 secured by fastening means 32 to the front 33 of a closed box 110 34. The front 33 is provided with flanges 35 slidingly engaging the bottom, sides and

top of the box 34. The flange 35 at the bottom of the front is connected by a hinge 36 with the forward end of a back plate 37 to which the flat back 38 of the form 30 is 5 detachably fastened by suitable tying means 39 similar to the tying means 28 previously mentioned. By the arrangement described the front 33 with the back plate 37 and form 30 can be drawn out and turned up to display the form 30 and the garment 40 draped thereon in upright position, as plainly shown in Fig. 5. It is understood that in this case the front 33 also forms a base for the form 30, and the back plate 37 forms a background for the garment 40 to heighten the 10 appearance thereof.

By reference to Fig. 5, it will be noticed that the boxes 34 may be piled up in tiers.

Having thus described my invention, I 20 claim as new and desire to secure by Letters Patent:—

1. A display device, comprising a box having a front, a bottom, back, sides and top, a half form adapted to support a garment to 25 be displayed and having a flat bottom and a flat back, means permanently fastening the said flat bottom of the half form to the rear face of the said box front, the latter forming a base for the said half form, a backplate

hinged at its forward edge to the lower end 30 of the said box front, the said backplate fitting into the box between the sides thereof and resting normally on the bottom of the box, the flat back of the half form resting 35 on the said backplate, and tying means detachably fastening the said half form back to the said backplate.

2. A display device, comprising a box having a bottom, sides, a back, a front hinged to the bottom and a cover having 40 flanges and adapted to hold the front in closed position, a half form adapted to support a garment to be displayed and having a flat bottom and a flat back, means permanently securing the said flat bottom of the 45 half form to the rear face of the said hinged box front, the latter forming a base for the said half form, a backplate hinged at its forward end to the lower end of the said box front, the said backplate fitting into 50 the box between the sides thereof and normally resting on the bottom of the box, the flat back of the half form resting on the said backplate, and tying means detachably fastening the said half form back to the said 55 backplate.

CHARLES I. OWEN.
